CLAIM

We claim the ornamental design for a bottle, as shown and described.

DESCRIPTION

FIG. 1 is a front elevation view of a bottle showing our design;

FIG. 2 is a top perspective view thereof;

FIG. 3 is a rear elevation view thereof;

FIG. 4 is a further perspective view thereof showing a bottom of the design;

FIG. 5 is a bottom view thereof;

FIG. 6 is a top view thereof; and,

FIG. 7 is a cross-sectional view taken along line 7-7 in FIG. 3.

The shade lines represent the three-dimensional contour of the design and are not intended to represent or indicate surface decoration. The broken lines in the figures form no part of the claimed design.
